UNITED STATES PATENT OFFICE.

ROBERT R. DUNLOP, OF COLUMBUS, OHIO, ASSIGNOR, BY MESNE ASSIGNMENTS, TO THE JEFFREY MANUFACTURING COMPANY, A CORPORATION OF OHIO.

ELECTRIC BRAKE.

1,091,738.

Specification of Letters Patent. Patented Mar. 31, 1914.

Application filed January 17, 1905. Serial No. 241,527.

To all whom it may concern:

Be it known that I, ROBERT R. DUNLOP, a citizen of the United States, residing at Columbus, in the county of Franklin and State 5 of Ohio, have invented certain new and useful Improvements in Electric Brakes, of which the following is a specification, reference being had therein to the accompanying drawing.

10 This invention relates to improvements in electro-magnetically operated brakes for conveyer or elevator systems adapted to prevent the too rapid descent of an elevator or conveyer under the action of gravity.

15 Figure 1 is a plan view of the upper part of said system. Fig. 2 is a diagrammatic view showing the electro-magnetic brake, the motor, and the electrical circuit. Fig. 3 is a plan view of the contact lever of the starting 20 box. Fig. 4 is a longitudinal sectional view thereof. Fig. 5 is a detail view of the over-load circuit-breaker 35.

25 1 represents a tipple adapted to deliver material to an elongated endless carrier or conveyer 2, which is inclined to the horizontal and is adapted to retard the descent under gravity of the material received.

30 3 is a trough in which the said conveyer operates.

35 4 represents a shunt-wound motor having an armature 5, the brushes 6 and 7 and the shunt motor field 8. The armature has secured to it a pinion 9 which meshes with a gear 10 secured to the head or driving shaft 11 at the upper end of the conveyer.

40 12 is a friction brake associated with the motor shaft. It may be of any well known type. In the drawings I have shown it comprising the casing 13 which is rigidly secured in position, the friction disks 14, arranged on the motor shaft and secured so as to revolve therewith but adapted to slide longitudinally thereon, the friction disks 15 arranged between the disks 14 and splined 45 to the casing 13 so as to be free to move longitudinally of the motor shaft but held from rotation therewith, the follower 16, the plate or head 17, and the springs 18 arranged between said follower and said plate and 50 adapted to normally hold the friction disks in engagement with each other so as to prevent the rotation of the motor shaft.

55 12' is an electro-magnet having the core 12^a fitted on to the motor shaft and having

one of its ends secured to the follower 16. 55 12^b is the energizing coil of the said electro-magnet. This electro-magnet 12' is designed for sufficient strength to draw the follower 16 against the action of the springs 18 so as to leave the elements of the clutch 12 60 free to rotate relative to each other. 19 is another friction brake likewise arranged upon the motor shaft, and adapted to control the rotation thereof. 20 indicates the stationary element of this brake and 21 the 65 movable element thereof. The latter is electromagnetically operated it having a tubular extension 21' which serves as the core of the electro-magnet 22, the coil 22' of which is arranged within the stationary element 20 of the brake. A suitable spring 19^a 70 may be interposed between the end of core 21' and the brake element 20, said spring tending normally to press the movable element 21 away from the stationary element. 75 This electro-magnet is designed for sufficient strength to draw the movable element 21 of the brake 19 into engagement with the stationary one 20 thereof. The brake 19 is not thrown into operation until the speed of rotation of the motor exceeds a certain predetermined rate and as soon as it does exceed this rate, the electro-magnet 22 is sufficiently energized by the current from the motor operating as a generator to cause the engagement 80 of the brake elements in such manner as to limit the speed of the motor shaft.

85 24 indicates a source of electrical supply, 24' and 24^a the positive and negative conductors, respectively, therefrom. 25 is a 90 single-throw, double-pole switch with terminals 25' and 25^a connected to said conductors 24' and 24^a respectively. 26 is a starting box having the operating lever 26'. 27 is a conductor leading from said lever to the 95 brush 6 of the motor.

28 is a conductor leading from the terminal of the resistance in the starting box to the pole 25^b of the switch.

28' is a conductor leading from the brush 100 7 to the pole 25^c of the said switch.

The field 8 of the motor has its terminals connected to the conductors 27 and 28' respectively.

29 indicates a series of resistance-control- 105 ling contacts on the starting box with which the lever 26' is adapted to engage. 30 is a contact on said box having its end 31 ex-

tending so that contact 31' on the lever 26' will engage with it prior to its engagement with the first contact of the series 29. This contact 31' is insulated from the said lever.

5 32 is a conductor connecting the said segment 30 with the conductor 28.

33 is a conductor connecting the contact 31' on the lever 26' with one terminal of the energizing coil 12^b of the electro-magnet

10 12'. 33' is a conductor connecting the other terminal of said coil with one terminal of the energizing coil 22' of the electro-magnet

15 22, and 34 is a conductor connecting the other terminal of said coil with the conductor

20 28' so that this coil is connected directly across the line when the motor is in operation either as a motor or as a generator.

35 is an overload circuit-breaker arranged in the line of the conductor 34, and 36 is an 20 adjustable shunt arranged across the terminals of the electro-magnet 22.

It will be seen that when the conveyer 2 is stationary and no current flowing through the energizing coils 12^b and 22' of the electro-magnet 12' and 22, respectively, that the friction brake 12 will be set so as to prevent the rotation of the motor shaft. In order to start the conveyer, the circuit-breaker 35 is closed and also the switch 25 and then the 30 current switching lever 26' of the starting box 26 is swung until contact 31' engages the end 31 of the contact 30. Current will then pass through the energizing coils 12^b and 22' of the electro-magnets 12' and 22, respectively, the former, drawing the follower 16 so as to release the friction between the friction disks of the brake 12 and the latter drawing the movable element 21 of the brake 19 toward the stationary element 40 20 thereof. This will enable the motor to start up free from the resistance of the friction brakes as the lever 26' engages with the first of the resistance-controlling contacts on the starting box and completes the 45 circuit to the motor.

As soon as the momentum of the retarding conveyer reaches a certain point, in order to prevent the too rapid descent of the conveyer, the source of supply from the generator to the motor is cut out and the motor operated as a generator, the fact that it is shunt-wound insuring that its field will be excited in the same direction as it was excited when supplied with current from the 50 said generator. The energizing coils 12^b and 22' of the said electro-magnets 12' and 22 being in parallel with field 8 will be energized by the current generated by the motor so as to operate the brake 19 and hold 55 the brake 12 out of operation. Should the speed of the armature shaft exceed a predetermined rate owing to the too rapid descent of the conveyer elements, the increased electro-motive force generated by the consequent increase of speed of rotation of the

armature will cause the engagement of the brake elements 20 and 21, and if the frictional resistance so occasioned is not sufficient to keep down the speed of rotation of the armature shaft, the electro-motive force generated will cause the overload circuit-breaker 35 to open, breaking the circuit to the electro-magnet and permitting the friction brake 12 to operate and stop the rotation of the motor shaft.

70 While it is contemplated that the current supply will be cut off when the machine has attained a certain speed, as stated above, it should be observed that the brake mechanism will operate in substantially the same manner if the current supply is not cut off. Assuming the mechanism operating with the switch 25 closed, when the dynamo-electric machine attains a certain speed its electro-motive force counter to that of the current source will become the greater of the two and it will then supply current to energize the electro-magnets in the same manner as if the switch were open. In other words, the dynamo-electric machine acts to apply the brake 19 both when connected to the current source to run as a motor and when disconnected therefrom.

75 The adjustable shunt 36 may be adjusted to vary the amount of current received by the energizing coil 22' of the electro-magnet 22 and thus regulate and control the operation of the brake 19.

80 Many modifications of the manner of completing the electrical circuit and in the use of differently wound motors will suggest themselves which will contain the spirit of my invention, I having herein described and shown but one of the uses to which it may be applied.

105 I claim—

1. The combination with a dynamo electric machine adapted to run either as a motor or a generator, a source of electric current supply and means for connecting said machine with and disconnecting it from said source of supply, of a friction brake arranged to normally oppose the rotation of the armature shaft of the said machine, an electro-magnet having its core connected with the movable element of said brake and adapted to release the brake from the dynamo electric machine when operated as either a motor or a generator, a second friction brake connected to the said armature shaft of the said machine, and a second electro-magnet having its core connected with the movable element of the last described brake and adapted when the machine armature exceeds a predetermined speed to actuate the said brake and retard the rotation of said armature both when the machine is connected to and disconnected from the said source of electric current supply.

110 2. The combination with a dynamo elec-

- tric machine adapted to run either as a motor or a generator, a source of electric current supply, means for connecting said machine with and disconnecting it from said source of current supply, of a friction brake arranged to normally oppose the rotation of the armature shaft of said machine, an electro-magnet having its core connected with a movable element of said brake and adapted to release the brake when the dynamo electric machine is operated either as a motor or as a generator, a second friction brake connected to the said armature shaft of said machine and a second electro-magnet having its core connected with the movable element of said last described brake and adapted when the machine armature exceeds a predetermined speed to actuate said brake and retard the rotation of said armature both when the said machine is connected to and when it is disconnected from the said source of electric current supply, the energizing coils of said magnets being connected in the circuit to the said dynamo electric machine. 3. The combination with a dynamo electric machine adapted to run either as a motor or as a generator, a source of electric current supply and means for connecting said machine with and disconnecting it from the said source of electric current supply, of a friction brake arranged to normally oppose the rotation of the armature shaft of said machine, an electro-magnet having its core connected with the movable element of said brake and adapted to release the brake when the dynamo electric machine is operated either as a motor or as a generator, a second friction brake connected to the said armature shaft of said machine, and a second electro-magnet having its core connected with the movable element of the said last described brake and adapted when the machine armature exceeds a predetermined speed to actuate the said brake and retard the rotation of the said armature both when the said machine is connected to or disconnected from the source of electric current supply, the energizing coils of the said electro-magnets being connected in series with each other and in the electrical circuit to said dynamo electric machine.
4. The combination of a motor, a friction brake connected with the armature shaft of said motor and arranged to normally prevent its rotation, manually controlled power actuated means for releasing said brake, a second brake connected with the armature shaft of said motor and adapted to oppose the rotation of said shaft beyond a predetermined speed, automatically operated means for actuating said second brake, and means for automatically applying the first named brake when the rotation of the motor exceeds the said predetermined speed.
5. The combination of a motor, a brake connected with the armature shaft of said motor and arranged to normally prevent its rotation, a manually controlled electro-magnetic means for releasing said brake, a second brake connected with the armature shaft of said motor and adapted to oppose the rotation of said shaft beyond a predetermined speed, automatically actuated means for operating said second brake, and means for automatically applying the first named brake when the motor shaft exceeds the said predetermined speed. 70
6. The combination of a motor, a friction brake connected with the armature shaft of said motor and arranged to normally prevent its rotation, an electro-magnetic means for releasing said brake, a second brake connected with the armature shaft of said motor and adapted to oppose the rotation of said shaft beyond a predetermined speed, electro-magnetic means for operating said second brake, and means for automatically applying the first named brake when the rotation of the armature exceeds said predetermined speed. 80
7. The combination of the motor, the friction brake adapted normally to prevent the rotation of the armature shaft of said motor, the electro-magnet for releasing said brake, the second brake connected with the armature shaft of said motor and arranged to retard the rotation of the said armature shaft when it exceeds a certain predetermined speed, and the electro-magnet for operating the last described brake, the energizing coils for both of said magnets being connected directly across the current supply line to the motor. 95
8. The combination of the motor, the friction brake adapted normally to prevent the rotation of the armature shaft of said motor, the electro-magnet for releasing said brake, the second brake connected with the armature shaft of said motor and arranged to retard the rotation of the said armature shaft when it exceeds a certain predetermined speed, and the electro-magnet for operating the last described brake, the energizing coils of the said magnets being connected in series with each other and directly across the current supply line to the motor. 105
9. The combination of the shunt wound motor, the brake connected with the armature shaft of said motor and arranged normally to prevent the rotation of said shaft, the electro-magnet for operating the said brake, the second brake connected with the said armature shaft and adapted to oppose its rotation above a certain predetermined speed, and the electro-magnet for operating the last described brake, the energizing coils of said magnets being connected in parallel with the motor field. 120
10. The combination of the motor, the 130

- friction brake connected with the armature shaft of said motor and arranged to normally prevent its rotation, the electro-magnet for releasing the said brake, the second friction brake connected with the said armature shaft and arranged to oppose its rotation above a predetermined speed, the electro-magnet for operating said brake, the energizing coils of the said magnets being connected in series and directly across the current supply line to the motor and the overload circuit breaker arranged in the circuit of the said energizing coils.
11. The combination of the motor, the friction brake connected with the armature shaft of said motor and arranged to normally prevent its rotation, the electro-magnet for releasing the said brake, the second friction brake connected with the said armature shaft and arranged to oppose its rotation above a predetermined speed, the electro-magnet for operating said brake, the energizing coils of the said magnets being connected in series and directly across the current supply line to the motor, the overload circuit breaker arranged in the circuit of the said energizing coils and the variable shunt in the circuit around the magnet coil of the second brake.
12. The combination of the motor, the friction brake adapted to normally prevent the rotation of the armature shaft of said motor, the electro-magnet for releasing said brake, the second friction brake arranged to oppose the rotation of the said armature shaft above a predetermined speed, the electro-magnet for operating the last described brake, the energizing coils of the said electro-magnets being connected in series with each other and also in the motor circuit, and the variable shunt interposed in the circuit around the magnet coil of the second brake.
13. The combination of the motor, the source of electric current supply, the brake connected with the armature shaft of the motor and arranged to normally prevent rotation of said shaft, means for releasing said brake, the second brake connected with the armature shaft and adapted to oppose its rotation above a predetermined speed, and the electro-magnet for operating the second brake, the motor and the energizing coils of said magnet being connected in parallel to the current source.
14. The combination of the motor, the source of electric current supply, the brake connected with the armature shaft of said motor and arranged normally to prevent rotation of said shaft, the electro-magnet for operating said brake, the second brake connected with the said armature shaft and adapted to oppose its rotation above a predetermined speed, and the electro-magnet for operating the last-named brake, the motor and the energizing coils of said magnet being connected in parallel to the current source.
15. The combination with a dynamo-electric machine, of two friction brakes connected with the armature shaft of said machine, one of said brakes being arranged to normally prevent rotation of said shaft and the other brake being arranged to oppose its rotation beyond a predetermined rate of speed, manually controlled power actuated means for releasing the first named brake, means for automatically applying said brake when the rotation of the armature exceeds said predetermined speed, and electro-magnetic means for causing the actuation of the other of said brakes.
16. The combination with a dynamo-electric machine of two friction brakes connected with the armature shaft of said machine, one of said brakes being arranged to normally oppose the rotation of said shaft and the other being arranged to oppose its rotation beyond a predetermined speed, and means for simultaneously releasing one and applying the other one of said brakes.
17. The combination with a dynamo-electric machine of two friction brakes connected with the armature shaft of said machine, one of said brakes being arranged to normally oppose the rotation of said shaft, and the other one being arranged to oppose its rotation beyond a predetermined speed, and means for automatically and simultaneously releasing the one and applying the other one of said brakes.
18. The combination with a dynamo-electric machine of two friction brakes connected with the armature shaft of said machine, one of said brakes being arranged to normally oppose the rotation of said shaft and the other one being arranged to oppose its rotation beyond a predetermined speed, and electro-magnetic devices operable simultaneously for releasing one of the brakes and for applying the other one.
19. The combination of a dynamo-electric machine, a source of electric current supply, two friction brakes connected with the armature shaft of said machine, one of said brakes being arranged to normally oppose the rotation of said shaft and the other one being arranged to oppose its rotation beyond a predetermined speed, electro-magnetic devices electrically connected in the electrical circuit to the said machine and mechanically connected to said brakes and adapted to release the first described one thereof and apply the second one, and means for connecting said electro-magnetic devices to the source of current supply prior to completing the circuit between said source and the said dynamo-electric machine.
20. The combination with a dynamo-electric machine of two friction brakes connected with the armature shaft of said machine,

- one of said brakes being arranged to normally oppose the rotation of said shaft and the other one being arranged to oppose its rotation beyond a predetermined speed, two 5 electro-magnets having their coils connected in series and to the electrical circuit for said machine, the movable core of one of said magnets being connected to the movable element of one of said brakes, and the movable core of the other of said magnets being connected to the movable element of the other one of said brakes, and the overload circuit breaker in the electrical circuit for said electro-magnets.
- 10 21. The combination with a dynamo-electric machine of two friction brakes connected with the armature shaft of said machine, one of said brakes being arranged to normally oppose the rotation of said shaft, and the other one being arranged to oppose its rotation beyond a predetermined speed, two 15 electro-magnets having their coils connected in series and to the electrical circuit for said machine, the movable core of one of said magnets being connected to the movable element of one of said brakes, and the movable core of the other of said magnets being connected to the movable element of the other one of said brakes, and the adjustable 20 shunt in the said circuit for the magnet coils arranged to shunt the current from the coils of the second one of said magnets.
- 25 22. The combination with a dynamo-electric machine of two friction brakes connected with the armature shaft of said machine, one of said brakes being arranged to normally oppose the rotation of said shaft, and the other one being arranged to oppose its rotation beyond a predetermined speed, two 30 electro-magnets having their coils connected in series and to the electrical circuit for said machine, the movable core of one of said magnets being connected to the movable element of one of said brakes, and the movable core of the other of said magnets being connected to the movable element of the other one of said brakes, and the adjustable 35 shunt in the said circuit for the magnet coils arranged to shunt the current from the coils of the second one of said magnets.
- 40 45 23. The combination of a motor, a source of current supply, a brake arranged to prevent the rotation of the armature shaft of the motor above a predetermined speed, an electro-magnet for operating the said brake, the energizing coils of the said magnet being connected to the source of current supply in parallel with the motor circuit, and a variable shunt arranged to control the operation of the brake, substantially as set forth.
- 45 50 24. The combination of a source of current supply, a dynamo-electric machine adapted to run either as a motor or a generator, means for connecting said machine with and disconnecting it from said source of supply, and an electro-magnetic brake for the armature of said machine having its windings connected in the circuit of said 55 machine and adapted to be energized to oppose the rotation of the armature when it exceeds a certain speed both when the machine is electrically connected to or disconnected from the source of electrical supply.
- 55 60 25. The combination of a source of electric current supply, a dynamo-electric machine adapted to take current from said source, a circuit for said machine adapted to be closed independently of the current 65 source, a brake normally opposing the rotation of the armature of the machine, electro-magnetic means electrically connected in the said circuit of the machine for releasing said brake, means for connecting the machine to the source of supply, and means connected with the last named means for closing the 70 said circuit and energizing the electro-magnetic means before the machine is connected to the source of supply.
- 75 80 85 90 In testimony whereof I affix my signature in presence of two witnesses.
